DRAIN STRUCTURE

Percy E. Knudsen and Lewis G. Diera, Pittsburgh,
Pa., assignors to Pittsburgh Plate Glass Com-
pany, a corporation of Pennsylvania

Application November 19, 1943, Serial No. 510,932

8 Claims.

(Cl. 206—2)

The present invention relates to drains for tanks or vats and it has particular relation to drains for vats or tanks lined with plate glass and containing acids or other highly corrosive liquids.

One object of the invention is to provide a drain of the foregoing type which is not subject to attack by corrosive acids.

A second object of the invention is to provide a drain which is simple and the joints of which are completely sealed from leakage.

These and other objects of the invention will be apparent from consideration of the following specification and the appended claims.

It has heretofore been proposed to provide tanks for acid, such as pickling acids and other corrosive liquids, having internal walls of glass and outer supporting walls of wood or metal. Considerable difficulty has been encountered in the provision of such tanks of a drain structure which is simple, inexpensive, which is not subject to rapid corrosion and deterioration, and in which leakage of the contents of the tank through imperfect joints is positively prevented.

In accordance with the provisions of the present invention it is proposed to overcome the foregoing difficulties by the provision of a drain structure including a section of drain-pipe having a base of glass plates secured thereto, which plates are sealed in mastic between the inner and outer walls of the tank and which base is provided with a cover plate, bolted to the outer walls in such manner that the base plates can be securely held against the inner wall of the tank.

For a better understanding of the invention reference may now be had to the accompanying drawings in which like numerals refer to like parts throughout and in which

Fig. 1 is a side elevational view of tank embodying the principles of the invention;

Fig. 2 is a sectional view showing on a larger scale one form of the drain structure;

Fig. 3 is a plan view of a suitable clamping plate for holding the drain structure in place;

Figs. 4, 5 and 6 are sectional views showing on a larger scale additional forms of the invention.

The construction as shown in Figs. 1, 2 and 3 comprises a tank 10, which may be of any suitable size and may be used, for example, as a container for pickling acids during metallurgical pickling operations. A part, e. g., the bottom of this container is shown in greater detail in Fig. 2 and includes an inner wall comprising a plate of glass of substantial thickness, e. g. $\frac{1}{2}$ inch, which is highly acid resistant. The glass may be tempered

or "Herculited." The walls include an outer reinforcing shell 12 of wood or the like, the inner surface of which is covered by a thin plate 13 of ordinary sheet glass. It will be noted that the inner shell or liner and the latter are substantially spaced to receive a packing 14 of asphalt which preferably is moderately high melting and which is poured into the space at a temperature of about 350 to 400° F., so that it will flow completely to fill all corners and cavities.

The drain structure 15 includes a pair of superposed glass base plates 16 and 17, which are bonded together by an intermediate layer 18 of acid resistant plastic. The plates are disposed in opening 20 in shell 12 so that the inner of the glass plates is embedded in the asphaltic packing 14 and may also be secured to the inner lining 11 by means of a thin annular layer 21 of acid-resistant plastic. The space about the layer 21 is run full of hot asphalt from layer 14. Registering openings 22, 23 and 24 are formed in the plates 11, 17 and 16 for the escape of liquids from the tank. It is to be observed that drain-pipe 25 is disposed in the opening 24 in the plate 16. At its rear edge it may engage a shoulder 27, provided by the edge of opening 23 in plate 17.

The pipe is also threaded or welded intermediate of its length as indicated at 28 in an opening formed in a clamping or cover plate 29, which is held in position in a rabbet 31 about opening 20 in the shell 12 by means of through bolts 32 disposed about the latter opening. The rear extremity of the tube is cushioned in the opening 24 from contact with the glass plate 16 and also the latter is cushioned from contact with the cover plate 29 by means of a layer 33 of glass cloth or fiber impregnated with asphalt or with a thermosetting plastic, such as urea-formaldehyde or phenol-formaldehyde or the like.

The space between the edges of the opening in the outer wall 12 and the edges of the plate 16 may conveniently be filled with acid-resistant thermosetting plastic 34, such as phenol-formaldehyde above referred to.

A valve structure for closing the drain may be comprised by a mere simple cork or stopper inserted in the opening 22 or it may include a valve or cap 35 upon the threaded end portion 36 of pipe 25. A perforated disc 37 constituting a strainer seats against the rear end of the pipe 25 in such manner that it can easily be removed for cleaning.

In Fig. 1, the use of the same drain structure in the side walls of the tank as an overflow pipe is illustrated at 38.

In the form of the invention disclosed in Fig. 4 the discharge pipe 40 is entirely of glass. The construction otherwise is very similar to the embodiment of the invention already described. It includes a tank having a liner 41 of relatively heavy plate glass, an outer reinforcing shell 42 preferably of wood and a facing 43 of light sheet glass covering the inner surface of the wood. The space between the sheet glass 43 and the plate glass liner 41 is filled with asphalt 44 poured in while hot and highly fluid.

The drain structure includes heavy glass base plates 46 and 47 superposed upon each other and disposed in openings 48 and 49 in the outer shell 42 and the plate 43. Preferably the asphalt is poured about the plate 46 and is flowed into the space between the back of the plate 41 and the inner surface of the plate 46 to provide a thin sealing layer 51. Openings 52 and 53 are formed in plates 41 and 46 in register with each other and in register with the bore of the discharge pipe 40. An annular space about these openings and between plates 41 and 46 is filled with a layer of thermosetting resin 54, which binds the plates together and also prevents the asphalt of the layer 51 from flowing into the opening during the pouring of the layer 44. It is to be observed that plates 46 and 47 are bonded together by layer 56 of acid-proof mastic and that the plate 47 is formed with an inwardly flared opening 57 receiving a correspondingly flared base portion 58 of the discharge tube 40. The forward portion of the pipe is of such diameter that it can conveniently be inserted through opening 57 before the base plates are cemented together. A secure unitary structure is thus obtained. The space between the base portion and the opening is packed and sealed by means of a layer 59 of glass cloth impregnated with a suitable acid-resisting thermosetting resin, such as phenol-formaldehyde or the like. It is to be observed that the bore of discharge tube 40 is slightly less in diameter than the opening 53, thus providing a shoulder portion 61 at the rear of the tube, against which a strainer 62 is seated.

The space between the edges of the opening 48 in the wood reinforcing shell 42 and the edges of the plates 46 and 47 may be sealed with mastic. In order positively to clamp the plates 46 and 47 in the position a cover plate 63 preferably of plywood is provided and has margins set in rabbeted portion 64 in the wood of the shell. The plate may be clamped or held by means of through bolts 66 extending through suitable holes in the shell and also the plate and having nuts 67 threaded thereupon. The drain may be closed in any convenient manner by means of a valve or more simply by means of a mere plug 68 of rubber or any other convenient corrosion-resistant material.

The construction shown in Fig. 5 substantially corresponds to that disclosed in Figs. 2 and 3, except that the wooden reinforcing shell has been replaced by a metal shell 70. The opening 71 in this shell for the drain structure is surrounded by a ring 72 of metal or the like welded to the shell, as indicated at 73 and having an annular flange 74 welded to the outer edge thereof. The cover plate 76 in this construction corresponds essentially to that of the plate 29 already described and the drain-pipe 77 is welded in an opening therein as indicated at 78. This drain may be closed by stopper or valve or as shown by means of a glass ball 79 having a pull chain or rod 81 connected thereto.

The construction disclosed in Fig. 6 essentially corresponds to that of Fig. 4 except that the wooden shell is replaced by metallic shell 85 which, as shown, carries a ring 86 welded about the opening for the drain structure having flange 87 to which cover plate 88 is secured by bolts 89. The glass discharge tube or pipe 91 in this structure is mounted essentially the same way as is the pipe 40 shown in Fig. 4. Additional description is not deemed to be necessary.

The use of the drain structures in the bottoms of tanks has been particularly emphasized. However, they can also be placed in the side walls, either as drains or as overflow pipes.

The constructions herein shown are simple and ideally designed for use in glass lined tanks. They are corrosion resistant to a high degree and are not subject to leakage about the joints.

The forms of the invention herein disclosed are to be regarded merely as exemplary. It will be apparent to those skilled in the art that numerous modifications may be made therein without departure from the scope of the invention or the spirit of the appended claims.

25. What we claim is:

1. In combination a container for corrosive liquids including an inner lining of plate glass, an outer reinforcing shell spaced therefrom, the space between the two being filled with a corrosion-resistant packing material, said inner lining being formed with a drain opening and the reinforcing shell having an opening of larger diameter registering with the drain opening, a drain structure including a glass base plate contiguous to the lining about the opening in the lining and being embedded in the packing material and carrying an outwardly-projecting drain-pipe and clamping means engaging the base plate and being secured to the reinforcing shell by means of 40 through bolts.

2. In combination a container for corrosive liquids including an inner lining of plate glass, an outer reinforcing shell spaced therefrom, the space between the two being filled with a corrosion-resistant packing material, said inner lining being formed with a drain opening and the reinforcing shell having an opening of larger diameter registering with the drain opening, a drain structure including a pair of superposed base plates having openings formed therein, registering with the drain opening, the inner of said base plates being embedded in the packing material, the opening formed therein being of less diameter than the opening in the outer plate, a drain-pipe seated in the opening in the outer plate and bearing against the edge of the opening in the inner plate and a cover plate disposed about the drain-pipe and being bolted to the outer shell.

3. In combination a container for corrosive liquids including an inner lining of plate glass, an outer reinforcing shell spaced therefrom, the space between the two being filled with a corrosion-resistant packing material, said inner lining being formed with a drain opening and the reinforcing shell having an opening of larger diameter registering with the drain opening, a drain structure including a pair of superposed glass base plates having openings formed therein, registering with the drain opening, the inner of said base plates being embedded in the packing material, the opening formed therein being of less diameter than the opening in the outer plate, a drain-pipe seated in the opening in the outer plate and bearing against the edge of the opening in the inner plate and a cover plate disposed about the drain-

pipe and being bolted to the outer shell, said drain-pipe and said cover plate being formed of metal and welded together.

4. In combination a container for corrosive liquids including an inner lining of plate glass, an outer reinforcing shell spaced therefrom, the space between the two being filled with a corrosion-resistant packing material, said inner lining being formed with a drain opening and the reinforcing shell having an opening of larger diameter registering with the drain opening, a drain structure including a pair of superposed glass base plates having openings formed therein, registering with the drain opening, the inner of said base plates being embedded in the packing material, the opening formed therein being of less diameter than the opening in the outer plate, a drain-pipe of glass seated in the opening in the outer plate and bearing against the edge of the opening in the inner plate and a cover plate disposed about the drain-pipe and being bolted to the outer shell, the opening in the outer of the glass base plates being inwardly flared and said drain-pipe being correspondingly flared, positively to key the two together in the assembled structure.

5. In combination a container for corrosive liquids including an inner lining of plate glass, an outer reinforcing shell spaced therefrom, the space between the two being filled with a corrosion-resistant packing material, said inner lining being formed with a drain opening and the reinforcing shell having an opening of larger diameter registering with the drain opening, a drain structure including a pair of superposed glass base plates having openings formed therein, registering with the drain opening, the inner of said plates being embedded in the packing material, the opening formed therein being of less diameter than the opening in the outer plate, a drain-pipe seated in the opening in the outer plate and bearing against the edge of the opening in the

inner plate and a cover plate disposed about the drain-pipe and being bolted to the outer shell, a perforate strainer plate engaged in the rear extremity of the drain-pipe.

6. A drain assembly for containers which containers have inner and outer walls, the space between being filled with an intermediate impervious packing and a drain opening in the inner wall, a larger registering opening in the outer wall, said assembly comprising two superposed base plates adapted to fit into the second opening and having openings therein adapted to register with the first opening, a cover plate having margins adapted to be bolted to the outer walls of said container, the cover plate having an opening formed therein coaxial with the openings in the base plates, a drain-pipe projecting through the outer of the base plates, said pipe projecting in the openings in said cover plate.

7. A drain assembly for a container, which container comprises an inner glass wall, an outer reinforcing wall spaced therefrom, and an intermediate impervious packing of fusible plastic material between the walls, said inner wall having a drain opening formed therein, said outer wall having a larger opening registering with the drain opening, said assembly including a pair of superposed glass base plates fitting into the latter opening and having registering openings formed therein, the outer of said base plates having the opening therein inwardly flared, a glass drain-pipe having a base portion fitting the opening in the outer base plate and a cover plate adapted to fit over the opening in the outer wall and having an opening receiving the drain-pipe, said cover plate being adapted to be bolted to the outer wall.

8. A construction as defined in claim 6 in which the drain-pipe and cover plate are of metal and are welded together to provide a unitary assembly.

PERCY E. KNUDSEN.
LEWIS G. DIERA.
